INVENTOR

William G. Kendall
BY Ade Bonville

ATTORNEY

UNITED STATES PATENT OFFICE.

WILLIAM G. KENDALL, OF NEWARK, NEW JERSEY.

POWDER PRESS.

Application filed December 4, 1925. Serial No. 73,172.

This invention relates to a powder press, and is an improvement of the powder press described in my application for Letter Patent of the United States, filed April 14th, 5 1924, Serial Number 706,379.

The object of the invention is the production of a machine, whereby a plurality of receptacles are filled one after the other with a predetermined measured quantity of powder 10 like rouge, the latter being pressed into each receptacle, with a portion thereof extending over its top edge with a spherical top surface. The adhesion of the particles of the rouge or other powder suffices to convert the 15 particles thereof into a compressed tablet, which is available for use by rubbing on its surface with a powder puff, cloth and the like. The second object of the invention is the production of a press with a pressing die, 20 the under surface of which is cleaned during the operation of the press, so as to form a tablet with a clean and smooth outer face. The third object of the invention is the production of a powder press with a rotatable 25 disc having measuring openings extending therethrough for receptacles and the powder to be compressed into the latter. The thickness of the disc with its holes, provide measuring means for the requisite quantity of 30 powder for each receptacle. The fourth object of the invention is the production of a press with a rotatable disc, provided with means to scrape off any powder that may be spilled thereon. The fifth object of the 35 invention is the production of a press with a pair of pressing dies operating simultaneously, the first die pressing powder into a receptacle, and the second pressing die again pressing the powder into said receptacle, to insure a clean smooth upper face for the 40 compressed powder.

In the accompanying drawings Fig. 1 represents a front elevation of an exemplification of the improved powder press; Fig. 2 shows a left hand side view of Fig. 1; Fig. 3 indicates an enlarged section of Fig. 1 on the line 3, 3; Fig. 4 shows an enlarged section of Fig. 3 on the line 4, 4; Fig. 5 shows a top plan view of some of the elements indicated in Fig. 4; Fig. 6 shows a left hand 45 side view of an element in Fig. 4; Fig. 7 represents an enlarged fragmentary portion of Fig. 1 partly in section; Fig. 8 shows a section of Fig. 3 on the line 8, 8 and Fig. 9 indicates a section of Fig. 8 on the line 9, 9. 55

The powder press is shown with the supporting frame comprising the similar legs 15 and 16, each of which terminates at its upper end in the curved edge 17. Pans 18 extend from the upper portions of said legs. 60 The body portion of the press comprises the members 20 and 21, which are connected by the cross piece 22. Bolts 23 connect said legs 15 and 16 to the members 20 and 21. 65 At the upper ends of the members 20 and 21 are formed journal bearings with the caps 25, for the shaft 26, with the wrist pin 27. A shelf 28 having the projection 28^a extends between and connects the members 20 and 21. Guide plates 30 are fastened to the front 70 ends of said members and form guides therewith for the cross head 31. A pair of pressing dies 36 and 37 each concaved at their lower end, with the former somewhat longer than the latter, extend from and are detachably secured to said cross head. The wrist pin 27 engages the connecting rod 40, which latter is in connection with the cross head 31. A plate 41 has one end supported upon and fastened to the upper faces of the members 20 and 21, and braces 42 support the other ends of said plate 41, and are in turn fastened to said members. An electric motor 43, in this instance, is supported upon and fastened to the plate 41. The armature 80 shaft 45 of the motor has fastened thereto the pinion 46. Journal lugs 47 extend from the said electric motor and have journaled therein the shaft 48. A spur gear 49 is fastened to one end of the shaft 48 and meshes 85 with the pinion 46. A pinion 50 is fastened to the other end of the shaft 48. A spur gear 51 is fastened to one end of the shaft 26 and meshes with the pinion 50. A spur gear 52 is fastened to the other end of the shaft 90 26. A bracket 53 with the journal bearings 54 is fastened to and extends from the plate 41. A vertical journal bearing 55 extends up from the bracket 53. A shaft 60 is journaled in the journal bearings 54, and to one 95 100

end thereof is fastened the pinion 61, which meshes with the spur gear 52, and to the other end of said shaft 60 is fastened the bevel gear 62. A pedal lever 63, with the 5 foot plate 64 has one end pivoted to the leg 16. A clutch lever 65 has one end pivoted to the member 21, and a connecting rod 66 has one end pivoted to the lever 63, and its other end is pivoted to the clutch lever 65, to control the usual clutch apparatus, between the spur gear 51 and the shaft 26. The rod 66 has fastened thereto a collar 67 and passes through a lug 68, extending from the member 21. A spring 69 encircles the rod 66 and 10 bears between the collar 67 and the lug 68. A table 70 is indicated with the projecting portion 71, which latter bears on the shelf 28 and is fastened thereto by means of the screws 72. Round openings 73, 74 and 75 15 are formed in the table 70 and the two latter also extend through the shelf 28. Elongated openings 76 are also formed in the table 70. A boss 77 with a threaded axial opening extends from the projecting portion 20 71. A waste chute 78 is formed in the upper face of the table 70. An apron 79 extends from the table 70 and a guide opening 80 is formed between said table and apron. An inclined delivery chute 81 extends from 25 30 and below the projection 71, with its upper portion below the opening 73. Supporting strips 82 and 83 respectively extend from the projection 71 for the pan 84, and from the strip 83 extends the pan 85.

35 A rotatable conveying disc 86 has formed at its axial center the hub 87, and in its periphery the locking openings 88. A plurality of conveying and measuring openings 90 extend through the disc 86 with their axial 40 centers on a circle struck from the axial center of said disc, and bisecting the angles formed by each pair of lines extending through the centers of the openings 90 and the said axial center of the disc. A shaft 45 91 has its lower portion fastened to the table 70 and extends through the disc 86 and its hub 87. A washer 92 encircles the shaft 91 and a nut 93 is provided for its upper end.

50 A charging hopper is indicated with the body portion 95, the chute 96 at its upper end and the nozzle shaped outlet portion 97 at its lower end. A stirrer shaft 100 extends up through said hopper and through the bearing 55. A collar 101 is fastened to the upper end of the shaft 100 and bears on the top end of the bearing 55. A bevel gear 102 is fastened to the shaft 100 and meshes with the bevel gear 62.

55 A rotating packer designated in its entirety by the numeral 105 comprises the upper sleeve portion 106, and the segmental shaped shoe 107, the plane of which latter is inclined to the longitudinal axis of the shaft 100. A screw 108 clamps the sleeve 60 65 portion 106 to the shaft 100.

The stirrer for the charging hopper comprises the shaft 100 already referred to, with the supporting bars 110, 111, and 112 extending therethrough. The said bars have formed at their ends the vertical slots 113, 70 to secure the pair of rods 115 inclined to each other, at their lower ends 116. A sleeve bracket 120 with the projecting flanges 121 and 122 is fastened to the lower end of the outlet portion 97 of the charging hopper. A bracket 123 is fastened to the flange 121 and to the table 70. A metallic flexible scraper or wiper 124 is fastened to the flange 122 and its lower edge bears on the disc 86. 75

80 A guide bracket 130 is fastened to the table 70, and has formed therewith at its upper end the guide sleeve 131. An ejector is indicated with the sleeve 132, which has formed therewith the concaved ejector die 133. A spindle 134 extends from the sleeve 132 and is guided in the sleeve 131. A collar 135 is fastened to the spindle 134 at its upper end. A spring 136 encircles the spindle 134 and bears between the collar 135 and the sleeve 131. An arm 140 extends from the cross head 31 and its other end is located over the collar 135. 85

85 A slide bar 141 with the unlocking pin 142 is guided in the guide opening 80, and has formed in its lower face the rack teeth 143. A guide plate 144 is fastened to the top face of the apron 79 to maintain the slide bar 141 in proper position. A pin 145 extends through the apron 79 and has fastened thereto the segmental gear 146 and the lever 147. The teeth of said segmental gear mesh with the rack teeth 143 of the slide bar 141. A connecting rod 152 has one end pivoted to the lever 147 and its other end is in pivotal connection with the spur gear 52. A latch 153 is pivoted to the slide bar 141 and is shown with the locking tooth 154 at one end, and the pin 155 at the other end. A spring 156 connects the pin 155 with a pin 157 extending from the slide bar 141. The tooth 154 is adapted to lock with the locking openings 88. A locking bar 160 is pivoted at one end to the top face of the table 70, by means of the pin 161. The bar 160 has formed at one edge thereof the concaved portion 162 and the locking heel 163, which latter is adapted to lock with the locking openings 88. A pin 164 extends from the bar 160 and a spring 165 connects the pin 164 and a pin 166 extending from the table 70. 110 115 120

125 An angle shaped supporting bar 175 is fastened to the cross member 22, and has formed in its outer end the clearance opening 176. A slide bar 178 is slidably supported on the bar 175. Guide strips 179 are fastened to the bar 175 for the slide bar 178. A wiper plate 180 with the opening 181 has one end fastened to the slide bar 178. An angle shaped block 182 with the vertical serrated leg 183 extends from the other end 130 135 140

and lower face of the plate 180. A movable clamping block 184 with the serrated face 186 is slidably connected to the block 182 by means of the screws 188. A wiper comprising a piece of fabric 189 is clamped between the blocks 182 and 184. A pin 190 extends from one of the guide strips 179, and a pin 191 extends from the wiper plate 180. A spring 192 connects the pins 190 and 191.

An arm 195 is fastened to the slide bar 141 and has formed therewith the heel 196, which latter coacts with the outer edge of the slide bar 178. A switch 198 is connected to the leg 16, for the wires not shown, to operate the electric motor 43.

The rouge pads to be produced are each designated in their entirety by the numeral 200, see Fig. 4. Each pad comprises the disc 201 shaped receptacle 201, having the tapered flange 202, and the compressed powder 203, with the spherical shaped upper face 204.

To produce the pads 200, the receptacles 201 are located in the openings 90 of the disc 86, between the ejector die 133 and the nozzle shaped outlet portion 97 of the charging hopper. The said hopper is charged with the powder, rouge or other material to be packed and compressed into said receptacles. The operator now starts the electric motor 43, by means of the switch 198, and then bears on the foot plate 64 to lock the spur gear 51 to the shaft 26, which then turns in the direction of the arrow A, see Fig. 2, and by means thereof the cross head 31 with the pressing dies 36 and 37 is reciprocated and the shafts 60 and 100 are turned. The shoe 107, the bars 110, 111 and 112 and the rods 115 revolve with the rotations of the shaft 100. The bars 110, 111, 112 and the rods 115 stir the powder in the charging hopper, which descends into the measuring openings 90 of the disc 86 when they are located under said hopper, and also fills and covers the receptacles 201 located in said opening 90 when in line with the charging hopper, and the rotating packer 105, by virtue of the inclination of its shoe 107 packs the powder into the receptacles. The pressing die 37 compresses the powder 203 into the receptacle 201 forming the spherical shaped upper face 204. At the same time the pressing die 36 again compresses the said powder in the receptacle located thereunder, to give it the proper finish. At the same time the ejector die 133 forces one of the finished rouge pads through the opening 90 in line therewith which falls through the opening 73 into the inclined chute 81, and from the latter the pads are gathered as a finished product. The ejector die 133 also functions as a safety device to maintain the openings 90 clear of receptacles that have been charged with powder between said die 133 and the charge

ing hopper, so that empty receptacles can be located in said designated openings to be conveyed under the charging hopper.

When the cross head 31 begins to rise, the segmental gear 146 and the lever 147 revolve in the direction of the arrow B, Fig. 2, and passes through the opening 181 of the wiper plate 180, and the slide bar 141 moves in the direction of the arrow C, (Fig. 3), and the locking tooth 154 of the latch 153 unlocks from its locking opening 88 of the disc 86, and the latter remains at rest, the disc 86 being locked in position by the heel 163 of the bar 160. When the unlocking pin 142 strikes the locking bar 160, the locking heel 163 is unlocked from its opening 88 in the disc 86. At the same time the tension of the spring 192 draws the slide bar 178 in the direction of the arrow D, and the wiper 189 bears against the bottom face of the pressing die 36 and cleans the same. When the cross head 31 starts to descend the segmental gear 146, Fig. 2, and the lever 147 revolve in a direction opposite the arrow B, and the slide bar 141 moves in a direction opposite to the arrow C and the opening 181 of the wiper plate 180 is located in proper position for the pressing die 36 to pass therethrough, by means of the heel 196. While the slide bar 141 is moving in a direction opposite to the arrow C, the tooth 154 of the latch 153, locks with one of the openings 88 of the disc 86 and moves said disc through an arc equal to a distance between a pair of its openings 88 to locate its openings 90 in proper position. While the cross head 31 is descending the arm 140 bears on the collar 135 of the spindle 134, and the ejector die 133 forces the finished rouge pad 200 through the opening 73.

It will be noted that while one receptacle 201 is being filled with its powder, the pressing dies 36 and 37 each compresses the powder in a receptacle located in line therewith, and the ejector die 133, discharges one of the finished rouge pads 200 from the machine. While the portion of the disc 86 is revolving from under the charging hopper to the location of the pressing die 37, the wiper 124 cleans the upper face of any powder spilled thereon and directs it to the waste chute 78, and from the latter it falls into the pan 85. During the rotation of the disc 86 the openings 76 allow any powder that may collect under said disc to fall into the pan 84. The opening 75 allows powder also to escape therethrough.

Various modifications may be made in the invention and the present exemplification is to be taken as illustrative and not limitative thereof. 125

Having described my invention what I desire to secure by Letters Patent and claim is:

1. In a powder press the combination of a shaft journaled therein, means to inter- 130

mittently rotate the shaft, a reciprocating cross head in the press coacting with said shaft, a table in the press with a plurality of openings for the escape of powder operated upon, a disc pivoted to the table and having a plurality of measuring openings extending therethrough adapted to convey receptacles for said powder, a slide bar guided in the table, means between the shaft and said slide bar to reciprocate the latter, means between the slide bar and disc to intermittently revolve the latter, means on said table to lock said disc in position at predetermined intervals, an ejector die normally slidably maintained over the path of the openings in said disc, means connected to said cross head to force said ejector die through the openings of said disc as they are located in line therewith and to force receptacles charged with powder therefrom, a charging hopper with its outlet end over said disc in the path of the openings thereof, a stirrer in said hopper, means interposed between said shaft and stirrer to turn the latter and a pair of pressing dies extending from said cross head in the path of the openings extending through said disc.

2. In a powder press the combination of a body portion, a shaft journaled in the body portion, a reciprocating cross head guided in said body portion and coacting with said shaft, a table in the press with a plurality of openings therethrough for the escape of powder operated upon, a disc pivoted to the table and having a plurality of measuring openings for said powder extending therethrough and having a plurality of locking openings in its circumferential edge, a slide bar guided in the table, means between the said shaft and slide bar to reciprocate the latter, a latch pivoted to the slide bar adapted to intermittently lock with the locking openings of said disc to move the latter, a pin extending from the slide bar, a locking bar with one end pivoted to the table and having a locking heel extending therefrom to lock with the locking openings of said disc, a spring with one end fastened to the locking bar and its other end fastened to said table to tend to force said locking bar to said disc to lock its heel thereto, said pin on the slide bar adapted to contact with said locking bar to disengage its heel from the locking openings of said disc, a guide bracket extending up from the table, an ejector die, a spindle for said die extending through the guide bracket, a spring for the spindle to force the die upwardly over the upper face of said disc, an arm extending from the cross head adapted to bear on the spindle of the ejector die to force the receptacles filled with compressed powder from said disc, a charging hopper over the disc to charge receptacles located in the openings thereof with powder, a pair

of pressing dies extending from said cross head to simultaneously compress the powder in a pair of receptacles contained in the openings of said disc and means connected to the hopper to clean the disc of any spilled powder, said pressing dies and ejector die functioning simultaneously.

3. In a powder press the combination of a disc having a plurality of openings extending therethrough, a reciprocating cross head in the press, a pressing die moving with the cross head in the path of the openings of said disc, the openings in the disc adapted to have receptacles located therein, means to charge said openings and receptacles with powder to be compressed in said receptacles by said pressing die, means to eject the receptacles from the openings in said disc after having the powder compressed therein, a slide bar guided in the press, means between the slide bar and disc to intermittently rotate the latter, a wiper plate slidably supported in the press, a wiper supported by said wiper plate to clean the bottom face of the pressing die, means between the slide bar and wiper plate to move the latter in one direction and other means to move it in an opposite direction.

4. In a powder press the combination of an intermittently rotated disc pivoted therein, said disc having a plurality of openings extending therethrough for receptacles, means to charge said openings and receptacles with powder, a reciprocating pressing die in the path of the openings of said disc to compress the powder into said receptacles, a reciprocating wiper plate in the press, a block extending from the wiper plate, a movable clamping block for the first block, means to secure a wiper between said blocks adapted to bear against and clean the bottom end of said pressing die, and means to eject the receptacles from the openings of said disc after having the powder compressed therein.

5. In a powder press the combination of an intermittently rotated disc pivoted therein, said disc having a plurality of openings extending therethrough for receptacles, means to charge said openings and receptacles with powder, a reciprocating pressing die in the path of the openings of said disc to compress the powder into said receptacles, a reciprocating wiper plate in the press, a block with a serrated leg extending from the wiper plate, a movable clamping block with a serrated face coacting with the first block, screws extending through the movable block in threaded engagement with the other block, a wiper clamped by the blocks adapted to bear against and clean the bottom end of said pressing die and means to eject the receptacles from said disc after having the powder compressed therein.

6. In a powder press the combination of a

table having openings for the disposal of any powder that may be spilled thereon, a rotatable disc having openings for receptacles and for charges of powder for said receptacles pivoted to the upper face of said table, a charging hopper with its outlet located over said disc and in the path of the openings thereof, a scraper bearing on the upper face of the disc to scrape off powder spilled thereon, a reciprocating cross head

guided in the press, pressing dies reciprocating with the cross head to simultaneously compress powder in the receptacles and means to eject the receptacles from the openings in said disc and from the press after the powder has been compressed in the receptacles. ¹⁵

In testimony whereof I affix my signature.

WILLIAM G. KENDALL.
